UNITED STATES PATENT OFFICE

LOUIS LUDWIG, OF BROOKLYN, NEW YORK

GUARD FOR HEATERS AND SIMILAR ARTICLES

Application filed March 24, 1931. Serial No. 524,875.

My invention relates to wire guards and more particularly to the means by which such guards are attached to the articles on which employed. The main object of my invention is to provide improved means for securing a guard to a heater or other article in such a manner that, while securely fastened and safe from displacement by vibration or sudden jars, it may still be easily detached when desired. A further object is to provide a guard of very simple and inexpensive construction.

These and other objects and advantages will be readily understood from the following description and from the accompanying drawings of a preferred embodiment in which, however, certain modifications may be made without departing from the scope of the invention. In the drawings

Fig. 1 is a plan view of the guard shown attached to the bowl of a so-called sun-bowl heater,

Fig. 2 is a side view of Fig. 1,

Fig. 3 is a fragmentary view of the bowl,

Fig. 4 is a fragmentary view of the guard frame, and

Fig. 5 is a fragmentary view of a slightly modified guard frame.

Figs. 3, 4 and 5 are drawn to a larger scale than the other views.

Referring now to the drawings, the bowl of a sun-bowl heater is shown at 10 and its circumferential flange at 11. Two sets of slots 12 and 13 are punched diametrically opposite each other in the flange 11. The guard consists of a ring 14 which is located concentric with a frame formed of two semicircular members 15 and 16. These members are connected to the ring by a plurality of curved rods 17. The ends of the rods are preferably welded to the frame members and the ring, but may be attached in any other suitable manner.

Referring now particularly to Fig. 4, the ends 18 of the frame members 15 and 16 are bent downward and folded back upon themselves so as to form a notch 18 and a detent 20. The notch is made of a width slightly greater than the thickness of the stock in the flange 11. The detents are slightly shorter

than the length of the slots 12 and 13. Instead of making the notch and detent as just described, the method shown in Fig. 5 may be employed. In that case a notch 21 is made by cutting into the bent end and thus forming the detent 22.

The ends of the frame members 15 and 16 are inserted in the slots 12 and 13 while the frame is sprung together by applying a light pressure on the curved rods in the directions indicated by the arrows 23. When the pressure is released the detents are securely clamped under the flange 11.

While I have shown the rods 17 connected to a concentric ring, it will be understood that this ring might be omitted and that diametrical rods might be connected from one frame member to the other. In that case the rods are connected together, at their intersection, by any suitable means.

Having described my invention, what I claim as new and wish to protect by Letters Patent is:

1. In a guard of the class described, two semicircular frame members forming a circular frame and having their ends spaced apart, a plurality of rods diametrically connecting with said frame members and attached to each other at their intersection, and the ends of the frame members bent to engage in openings formed in the article on which the guard is employed, the distances between the openings being different to the distances between the bent ends of the frame members.

2. In a guard of the class described, two semicircular frame members forming a circular frame and having their ends spaced apart, a plurality of curved rods diametrically connecting said frame members and attached to each other at their intersection, the ends of the frame members bent to engage in openings formed in the flange on the article on which the guard is employed, and detents formed on said bent ends for engagement under said flange, the distances between the openings being different to the distances between the bent ends of the frame members.

3. In a guard of the class described, two semicircular frame members forming a circular frame and having their ends spaced

- apart, an annular member located concentrically with the said frame members, a plurality of radial rods securing the frame members to the annular member, and the ends of said frame members bent to engage in openings formed in the article on which the guard is employed, the distances between the openings being different to the distances between the bent ends of the frame members.
10. 4. In a guard of the class described, two semicircular frame members forming a circular frame and having their ends spaced apart, an annular member located concentrically with the said frame members, a plurality of curved rods radially connected between the frame members and the annular member, the ends of said frame members bent to engage in openings formed in the flange on the article on which the guard is employed, and detents formed on said bent ends for engagement under said flange.
15. 5. In combination with a sun bowl heater having a plurality of spaced openings formed in its outer flange, a plurality of arcuated frame members together forming a circular frame, a plurality of radial rods each having one end fastened to one of said frame members, the other ends of all of said rods secured to a substantially concentrically located supporting member, and the ends of the frame members bent for engagement in the openings in said heater flange, the distances between the openings being different to the distance between the bent ends of the frame members.
20. 6. In combination with a sun bowl heater having a plurality of spaced openings formed in its outer flange, a plurality of arcuated frame members which together form a circular frame, a plurality of curved radial rods each having one end fastened to one of said frame members, the other ends of all of said rods secured to a substantially concentrically located supporting member, the ends of all the frame members bent to engage in the flange openings, and detents formed on said bent ends for engagement under said flange.

LOUIS LUDWIG.
